[57] CLAIM

The ornamental design for a soap storage dish, as shown and described.

DESCRIPTION

FIG. 1 is a top plan view of a soap storage dish showing my new design;

FIG. 2 is a front elevational view thereof;

FIG. 3 is a bottom view thereof;

FIG. 4 is a sectional view taken in the direction of the arrows on line 4—4 of FIG. 1;

FIG. 5 is a rear elevational view thereof; and

FIG. 6 is a sectional view taken in the direction of the arrows on line 6—6 of FIG. 1;

FIG. 7 is a right end elevational view thereof, the left end elevational view being a mirror image thereof.
